PROPELLER TEMPLATE

Vasili S. Drake, San Diego, Calif.

Application December 2, 1947, Serial No. 789,260

4 Claims. (Cl. 33—174)

(Granted under Title 35, U. S. Code (1952),
sec. 266)

1

This invention relates to propeller blade templates, and more particularly to an adjustable template which may be employed in the checking of practically all types of propeller blades.

In the fabrication and repair of propeller blades it is essential that the pitch of the blade at various points along the length thereof be determined accurately. This operation is performed, on a demounted propeller, by securing the propeller to a table, with the propeller shaft vertical and the blade to be checked extending over and above the surface of the table. A protractor is then positioned a predetermined distance away from the shaft axis, and the inclination of the propeller surface, on a line normal to the blade axis, is measured. This inclination, known as propeller pitch, is measured at predetermined radii from the propeller shaft, in accordance with a standard table established by the propeller designer.

When the under face, i. e. that facing the table, of the blade is formed of a straight line generatrix, a simple protractor having a straight abutting edge may be used. When, however, the under face of the plate is curved in accordance with air foil considerations, means must be interposed between the protractor straight edge and the propeller face to insure that the protractor edge will be exactly parallel to a line through the center of the propeller section.

It is an object of the instant invention to provide a template which may be positioned against a propeller blade to derive a straight edge which will be exactly parallel to the center line of the propeller section, and which may be used on propellers having differing contours.

It is another object of this invention to provide a universal template which may be used in pitch measurements of practically all types of propellers manufactured.

It is a further object of this invention to provide a template of simplified and rugged construction which may be mounted on a protractor for pitch measurement of practically any type of propeller.

In accordance with the instant invention, the template is constructed having three points of abutment against a propeller, thereby providing positive yet unambiguous positioning of the template against the propeller. Two of the points are relatively fixed and permanent; the third point is variable, thereby adapting the template for use with practically any known type of propeller. This third abutment point is part of an adjustable abutment holder which is so

2

mounted on the template that the third abutment point has two degrees of adjustability, i. e. may be adjusted both longitudinally and transversely of the template.

5 Two exemplary embodiments of the instant invention will now be described with reference to the accompanying drawing, wherein:

Fig. 1 shows a first embodiment of the instant template mounted on a protractor and applied to a propeller. Fig. 1 is taken generally along line 1—1 of Fig. 2;

Fig. 2 is a plan view showing more generally how the template is applied to the propeller;

Fig. 3 is an enlarged detailed view, showing an alternative type of abutment member constituting the third or variable abutment surface; and

Fig. 4 is a section taken along line 4—4 of Fig. 3.

Referring to the drawing, 11 designates the cross section of a propeller blade, against which is pressed the template 12, comprising a bar 13 having at one end thereof a transverse abutment post 14 forming an abutment surface for the leading edge 15 of the propeller 11. A second abutment surface or point is formed of a button 16 mounted at the edge of a step portion 17 positioned at the intersection of the bar 13 and the post 14. If desired, the parts 13, 14, and 17 may be made integral, although it is preferred to form the button 16 of a separate piece so that it may be fabricated to closer tolerance.

The two points of abutment thus described require only a third abutment point, spaced therefrom, to assure that the template may be placed in positive yet unambiguous position against the propeller 11. In the Fig. 1 embodiment this third point is provided by a cam 21 fixed to a shaft 22 journaled between a pair of plates 23 which embrace the bar 13 and constitute a slider 24 longitudinally adjustable along the bar. The plates 23 protrude transversely above and below the bar 13, and it is in the upper protruding portions that the shaft 22 is journaled.

45 A crank 25, affixed to one end of the shaft 22, provides convenient means for rotating the cam 21 and for thereby determining the distance, transverse of the bar 13, at which the third abutment point 26 of the template 12 will come to rest against the propeller 11.

Slider 24 may be moved back and forth along the bar 13 and locked in pre-selected position by means of a set screw or locking screw 27 threaded through one of the plates 23. Transverse indices 28 are marked along the bar 13 cooperable

with one of the edges, e. g. edge 29, of the slider 24 to aid in positioning the slider along the bar. One degree of positioning of the abutment point 26, i. e. longitudinally of the bar 13, is thus determined.

The other degree of positioning of the abutment point 26, i. e. transversely of the bar 13, is determined in discrete steps by the provision of a series of recesses 31 in the outer surface of one of the plates 23, disposed circumferentially adjacent the end of the crank 25, which is provided with a suitable form of spring pressed detent (not shown) engageable in the recesses 31.

The lower protruding portions 33 of the plates 23 constitute a bifurcated bracket, which may be fitted over a protractor bar 34 and firmly affixed thereto by a set screw 35, threaded through one of the plates 23. A similar mounting arrangement is provided adjacent other end of the bar 13 in the form of a pair of mounting plates 36 fixedly secured to the bar 13 and embracing the protractor bar 34, to which they may be selectively locked by a set screw 37.

Operation

The manner of use of the protractor illustrated in Fig. 1 will now be described, with reference to Figs. 1 and 2.

The propeller 41 to be checked is mounted with its shaft 42 vertical and with one of the blades 11 extending over the surface of a table 43. At a predetermined radius from the shaft 42, determined by the specifications of the propeller designer, the template 12 is positioned beneath the blade 11. Prior to this step the slider 24 has been locked by set screw 27 at the proper index 28, as prescribed by the propeller designer. Likewise, the end of the crank 25 has been set in the proper recess 31, pursuant to designer's requirements, thus placing the upper surface of the cam 21 as predetermined distance from the bar 13. The third abutment point 26 has thus been disposed, in accordance with the requirements of the propeller designer, so that for the particular propeller 11 being measured, the section center line 44 of the propeller 11 will be, when all three abutment points are engaged, exactly parallel to the protractor bar 34, when the template 12 is mounted thereon.

After positioning the template 12 against the propeller 11, the operator moves the protractor 45, including its protractor bar 34, into position and clamps it to the template 12, now employing the set screws 35 and 37. Height adjustability of the protractor 45 above the table 43 may be accommodated by suitable means such as telescoping of the protractor standard as shown at 46. The blade 11 is then checked at each of the several prescribed radii, the transverse and longitudinal settings of the abutment point 26 being varied as specified.

The blade 11 may be, and is generally, checked while mounted to the airplane. The instant device is equally suitable for such operation. In this case a protractor adapted for use on a mounted propeller is employed. An example of such a protractor is illustrated in Whitechester Patent 2,383,527. The instant template is inserted between the straight edge of the Whitechester protractor and the curved blade contour, in a manner similar to that described immediately above.

Modification

The manner for achieving transverse adjustability of the point 26 shown in Fig. 1 is only one

of several suitable arrangements that may be employed. Another satisfactory way of achieving the same result is shown in Figs. 3 and 4, wherein the shaft 22' of the slider 24' has mounted thereon a spoke-like abutment member 51, each of the arms 52 of which has a different length, thereby providing a series of differing transverse spacings for the abutment point 26.

As shown in Fig. 4 the shaft 22' is conveniently rotated by means of a crank 25', and is locked in preselected position by a knurled lock nut 53. The plates 23' of the slider 24' are secured together in position embracing the bar 13 by a pair of spacers 54 and 55, the bottom of the latter being the surface providing a seat for the template 12 against the protractor bar 34. It will be understood that the slider 24 of Fig. 1 appears in cross section much as shown in Fig. 4 for the slider 24'.

From the above description it will be seen that there has been described a template for the checking of propeller blade pitch having practically universal application to all types of airplane propellers.

Obviously many modifications and variations of the present invention are possible in the light of the above teachings. It is therefore to be understood that within the scope of the appended claims the invention may be practiced otherwise than as specifically described.

The invention described herein may be manufactured and used by or for the Government of the United States of America for governmental purposes without the payment of any royalties thereon or therefor.

What is claimed is:

1. A propeller blade template comprising a bar having abutment means adjacent one end thereof of against which a propeller blade may abut, a slider slidable along said bar, said slider being comprised of a pair of plates embracing said bar and protruding transversely therefrom and means connecting said plates to hold the slider to said bar, a shaft extending through a protruding portion of said plates, and an abutment cam mounted on said shaft and rotatable about the axis thereof, whereby one end of said bar may be spaced at selectively differing distances from the blade.
2. A propeller blade template comprising a bar having abutment means adjacent one end thereof of against which a propeller blade may abut, a slider slidable along said bar, said slider including a pair of plates embracing said bar and protruding transversely from each side thereof and means connecting said plates to hold the slider to said bar, a shaft extending through a protruding portion of said plates, a non-circular abutment member rotatably mounted on said shaft in edge-wise relation thereto and having a plurality of points on its periphery adapted to bear against the blade and spaced at differing radii from said shaft, whereby one end of said bar may be spaced at selectively differing distances from the blade, and a set screw threaded thru the other protruding portion of one of said plates for securing said bar to a protractor.
3. A propeller blade template comprising a bar having abutment means adjacent one end thereof of against which a propeller blade may abut, a slider slidable along said bar, said slider being comprised of a pair of plates embracing said bar and protruding transversely from each side thereof and means connecting said bar, a locking screw threaded thru one of said plates and oper-

able to lock said slider in selected position along said bar, a shaft extending through a protruding portion of said plates, an abutment cam mounted on said shaft and rotatable about the axis thereof, whereby one end of said bar may be spaced at selectively differing distances from the blade, means for locking said abutment cam in selected position to said slider, and a set screw threaded thru the other protruding portion of one of said plates for securing said bar to a protractor.

4. A propeller blade template comprising a bar having means adjacent one end constituting a two point abutment for a propeller blade to be measured, a slider comprised of two plates circumjacent said bar with cross members securing said plates together and permitting sliding movement of said slider along said bar, a set screw threaded thru said slider for clamping said slider to said bar at selected points, a shaft extending between said plates, a cam mounted on said shaft between said plates and rotatable about the shaft axis, a crank on one end of said shaft having a detent pressed toward the adjacent plate, and a series of circumferentially spaced recesses adja-

cent said detent for providing discrete positioning points for said arm, and hence for said cam.
